UNITED STATES PATENT OFFICE.

HENRY R. BREMER, OF KANSAS CITY, MISSOURI.

COMPOUND-SCREW-POWER DEVICE.

Application filed December 18, 1922. Serial No. 607,617.

To all whom it may concern:

Be it known that I, HENRY R. BREMER, a citizen of the United States, and resident of Kansas City, county of Jackson, State of Missouri, have invented a certain new and useful Improvement in Compound-Screw-Power Devices, of which the following is a complete specification.

This invention relates to a compound-screw power device and has for its object to produce mechanism whereby the power produced by the reciprocation of a piston may be transferred and imparted through a screw, the resulting force being greater than if the force of the piston was transmitted directly as reciprocating motion.

It is well known in mechanics that power transmitted through a screw is increased in proportion to the distance travelled by the actuating force in comparison with the distance travelled by the screw, and the chief object of this invention is to take advantage of this fact, and to produce a mechanism whereby such a result may be attained in a small and relatively compact mechanism.

With the object named in view, the invention consists in certain novel and useful features of construction and organization of parts as hereinafter described and claimed; and in order that it may be fully understood, reference is to be had to the accompanying drawing, in which:

Figure 1 is a face view of a mechanism embodying the invention as it will appear in use, and which for convenience is illustrated as used in conjunction with a punch;

Figure 2 is a section taken on the line II of Figure 1;

Figure 3 is a section taken on the line III—III of Figure 2;

Figure 4 is a section on the line IV—IV of Figure 2; and

Figure 5 is a reduced sectional view taken through the piston and cylinder to illustrate certain piston ports.

In the said drawing, where like reference characters identify corresponding parts in all of the figures, 1 illustrates a cylinder, to the lower end of which is secured a base portion 2, terminating in a foot 3 formed with an opening for the reception of any common or well-known type or female die 4.

Bolted or otherwise secured to the upper end of the cylinder is a cap member 5 formed with a handle 6, said handle being formed with a pair of bores or passages 7 and 8 for

the reception of slide valves 9 and 10, and vertically above said valves 9 and 10 are a pair of horizontal fluid passage-ways 11 and 11^a, the passage-way 11 being in communication with the atmosphere at one of its ends, and the passage-way 11^a is in communication with a suitable source of fluid supply under pressure (not shown).

Communicating with the bores 7 and 8 near their opposite ends and extending vertically downward are passage-ways 12^a and 12, respectively, each pair of passage-ways being united by horizontal passage-ways 13 and 13^a respectively, at their lower ends.

Upon referring to Figure 4, it will be found that the bores 7 and 8 are of unequal length, the former being somewhat longer than the latter, and that, therefore, the valves 9 and 10 are of unequal length, the former being the longer, and said valve 9 is provided near its opposite ends with openings 15 which at certain times are adapted to permit of communication between the passage-ways 11^a and 12^a and 11 and 12; and that the valve 10 is formed with a single opening 16, which is at times adapted to permit of communication between the passage-ways 11 and 12, at which time the opposite end of said piston will close communication in the other end of the handle between passage-ways 11 and 12^a, as will be readily understood, upon an inspection of the drawing, (more particularly Figure 4).

Pivoted to the handle at any convenient point is a control trigger 17, adapted to force the valves 9 and 10 inwardly, said valves and handle being returned to normal position by means of coiled springs 18 pressing at one of their ends against the device and at their opposite ends against suitable collars pinned or otherwise securely fixed in the extremities of the valves.

In communication with the cross channels 13 and 13^a respectively, are a pair of vertical passage-ways 19 and 20, formed in the side walls of the cylinder, the former terminating in an upturned portion 21 and the latter in a downwardly angling portion 22, and each communicating with the interior of the cylinder 1.

Extending through the cylinder 1 is a piston rod 23 formed at its upper end with a bearing portion 24 slidingly received within a socket formed in the cap 5. The piston rod is formed with a double spiral thread 25 of rather great pitch and preferably

formed with straight walls, and extends downwardly through the base 2, and has threaded engagement with said base as at 26, the threads in this instance being of 5 relatively small pitch as compared with the threads 25. It will be apparent from the construction just-described, when rotation is imparted to the rod, that the threads 26 will feed the rod downwardly, and in order 10 to accommodate this downward movement, the base is formed with an enlarged chamber 27 into which the lower portion of threads 26 will be received.

The lower end of the piston rod is provided 15 with a suitable bearing collar 28 fixedly secured to the base, and clamped between said base and collar is a packing 29 of any suitable or desired character. The lower end of the rod is connected to a coupling 30 of any suitable character, and carried by said coupling is a punch bit 31, in the device as illustrated. The drawing indicates a bit which ceases to rotate immediately the bit comes into contact with the 25 work, but it will be readily understood, that if found desirable, a bit which rotates may be employed.

Threaded on the rod 23 is a piston 32 provided with piston rings 34 as common, 30 and also provided at its opposite sides with a pair of tongues 34^a, for holding the piston against rotation, projecting from the piston and adapted for travel within a pair of channels 35 formed in the opposite walls of 35 the cylinder, see Figure 3. The piston is also provided with ports 37 and 38 adapted for communication respectively, with the ports 21 and 22.

The operation of the device is as follows: 40 With the parts standing in the position shown in Figure 2, fluid under pressure is permitted to enter the passage-way 11^a and it immediately passes downwardly through the opening 15 of the valve 9, the passage-way 12 and into the cross passage-way 13^a 45 and down through passage-way 19 and exits through the port 21 into the port 37 of the piston which, at this time is in register with the port 21, and thus into the cylinder above the piston.

Pressure is thus imposed on top of the piston and forces it downward. As the piston is held against rotation, as above-described, its threaded engagement with the rod will impart rotary movement to the latter, and with the proportions illustrated, the rod is revolved one complete revolution in the course of travel of the piston, and this rotary movement of the piston causes it to 50 be fed downwardly by the threads 26 in engagement with the base, as will be readily understood. Just prior to the time the piston attains its limit of travel, a fluid cushion is interposed between it and the 55 lower end of the cylinder, as will be de-

scribed in connection with the upward travel of the piston.

During the entire downward movement of the piston, except for the short time that the cushion is created, the lower end of the 70 cylinder is in communication with the port 22, passage 20, cross-passage 13^a, passage 12^a, the end of the bore 8 (see Figure 4), and the passage 11 and thus to the atmosphere. 75

As soon as the piston has reached its limit of downward movement, the operator operates the trigger 17 and causes the valves 9 and 10, to be shifted to the left, referring to Figure 4, which places the upper end of 80 the cylinder in communication with the atmosphere through the port 21, passage 19, passage 13, passage 12, the opening 16 in the valve 10, and thus to the passage 11 and the atmosphere; and at the same time opening 85 15 in the valve 9 places the passage 11^a in communication with the passage 12^a, passage 13^a, passage 20, port 22 and port 38 of the piston. The piston is now driven upwardly as will be readily understood, and during 90 its upward movement, of course, returns the rod to its original position for further operation.

Referring to Figure 5, it will be found the parts are so proportioned that on each 95 reciprocation of the piston at both ends of its stroke a small quantity of fluid is trapped by the end of the piston cutting off port 21 before piston port 37 or 38 registers respectively with ports 21 or 22. This trapped 100 material provides a fluid cushion as is well-known in the art, and the trapped fluid will escape when the piston movement brings the ports 37 and 21 or 38 and 22 into communication. 105

It will be apparent from the above description that the same general construction may be employed for a number of different purposes, and while I have described and claimed the preferred embodiment of 110 the invention, it is to be understood that I reserve the right to make all changes properly falling within the spirit and scope of the appended claims.

What I claim is:

1. In a power device, a threaded support, a rod having two threads of different pitch, that of the lesser pitch engaging the thread of the support, and means for movement on the rod and engaging the threaded portion 120 of greater pitch to impart rotation to said rod which is consequently moved longitudinally by its threaded portion in engagement with the support.

2. In a power device, a threaded support, 125 a rod having two threads of different pitch, that of the lesser pitch engaging the thread of the support, means for movement on the rod and engaging the threaded portion of greater pitch to impart rotation to said rod 130

- which is consequently moved longitudinally by its threaded portion in engagement with the support, and slidable means for actuation by the endwise movement of the rod.
- 5 3. In a power device, a threaded support, a rod having two threads of different pitch, that of the lesser pitch engaging the thread of the support, means for movement on the rod and engaging the threaded portion of 10 greater pitch to impart rotation to said rod which is consequently moved longitudinally by its threaded portion in engagement with the support, and a punch swivelled to one end of the rod.
- 15 4. In a power device, a support having a threaded bore and a piston cylinder at one end of said bore, a rod extending through said cylinder and journaled at one end in the support and having a thread engaging 20 the threaded bore and a second thread within the cylinder, a piston for reciprocation within the cylinder longitudinally of the rod, and engaging the said second thread thereof and interlocked with the cylinder 25 against rotation.
5. In a power device, a support having a threaded bore and a piston cylinder at one end of said bore, a rod extending through said cylinder and journaled at one end in the support and having a thread engaging 30 the threaded bore and a second thread within the cylinder, a piston for reciprocation within the cylinder longitudinally of and
- having threaded engagement with said rod for rotating the same and interlocked with 35 the cylinder to prevent rotation, and means for controlling the admission of fluid under pressure to either end of said cylinder.
6. In a power device, a support having a threaded bore and a piston cylinder at one 40 end of said bore, a rod extending through said cylinder and journaled at one end in the support and having a set of right and a set of left hand threads, one of said sets of threads being in engagement with the 45 threaded bore, and a piston for reciprocation within the cylinder and having threaded engagement with said second set of threads and interlocked with the cylinder to prevent rotation.
7. In a power device, a support having a threaded bore and a piston cylinder at one 50 end of said bore, a rod extending through said cylinder and journaled at one end in the support and having a set of right and a set of left hand threads, one of said sets of threads being in engagement with the threaded bore, a piston interlocked with the cylinder for reciprocation within the cylinder and having threaded engagement with 55 said second set of threads, and means for controlling the admission of fluid under pressure to either end of said cylinder.

In witness whereof I hereunto affix my signature.

HENRY R. BREMER.
